UNITED STATES PATENT OFFICE

WOLFGANG KNOCHENHAUER, OF WERNIGERODE, GERMANY

INTERNAL-COMBUSTION ENGINE

Application filed March 9, 1929, Serial No. 345,826; and in Germany March 10, 1928.

This invention relates to an internal combustion engine, in which the air for combustion is sucked into the working cylinder on the side of the stuffing box and conducted 5 from this cylinder, by a low pressure conduit arranged at the outer side of the working cylinder, into a compressor cylinder, from which it flows highly compressed and highly heated through a valve box and along 10 a fuel nozzle into the working cylinder at the side opposite the suction side.

In the improved engine the working cylinder, in which the constant pressure combustion and subsequent expansion of the compressed combustion gases takes place, has not to carry out any compression work. This is carried out in the compressor under the working cylinder, and the sucking in of 15 fresh air takes place on the other side of the working piston, while at the same time the combusted and expanded gases are expelled by this piston. In this manner one power stroke is carried out at every crank rotation, and a good volume efficiency is obtained at the same time.

An internal combustion engine constructed according to the invention is illustrated by way of example in the accompanying drawing in which:

Fig. 1 is a diagrammatical longitudinal section.

Fig. 2 shows in front elevation the crank shaft with connecting rods and pistons.

A short cylinder *a* is arranged in a crank case *b*, accurately in the same manner as in the commonly used vertical four stroke cycle engines. The piston *c* in the cylinder *a* is coupled to the crank shaft *d* also in the usual manner, the stroke being however specially short. The cover of the cylinder *a* is constructed like a valve box *e* serving at the same time as cover for an upper cylinder *f* of similar inner diameter but having a stroke about three times longer than that of the cylinder *a*. The cylinder *f* is the working cylinder proper, however without a compression space. The working side of the piston *g* is on the lower end. The piston *g* has on the top end a piston rod *h* traversing 50 a cover plate *i* which closes the upper end of

the cylinder *f*. The very resistant piston rod *h* is guided in an accordingly resistant stuffing box *j*. This piston rod *h* has at its top end a transverse piece *k* which is horizontal and projects symmetrically at both sides over the cylinder walls. At each end of the transverse piece *k* a pin *k'* for a connecting rod *l* projects. The connecting rods *l* act on both sides of the cylinders on the crank pins *d'* of the accordingly offset crank shaft. The two crank pins *d'* are disposed 180° plus the injection angle with regard to the stud *d* for the compressor cylinder so that the piston *c* is still about 50° distant from the upper dead centre when the working piston *g* is at the lower dead centre. The valve box *e* between the two cylinders *a* and *f* contains hollow spaces for water cooling. The cooling water flows further around the working surfaces of the cylinders.

The engine operates in the following manner:

The air for combustion is sucked in at the side of the stuffing box *j* of the working cylinder *f* through a suction valve *m* and then forced from the cylinder *f* through a pipe conduit *n* acting as low pressure conduit into the space which has in the meantime been liberated by the piston *c* of the compressor cylinder *a*. At the same time a pre-compression takes place according to the smaller volume of this cylinder. The final compression is effected by the compressor piston *c* which then ascends. This final pressure is attained as soon as the working piston *g*, after having sucked in again fresh air, arrives at its lower dead centre. From this moment the air compressed and highly heated is forced into the working cylinder *f* so that it flows close along the fuel nozzle *o*. Into this jet of hot air the fuel, previously heated to ignition temperature, enters so that it is instantaneously completely combusted. At the moment at which the compressor piston *c* passes through the upper dead centre the fuel injection is completed.

The gases from combustion expand then, until the exhaust valve *r* opens in a manner known per se shortly before the upper dead centre and equalization of the pressure takes

place, whereupon the waste gases are expelled by the piston when the same is moving back. During this backward movement of the piston fresh air is sucked in again on the other piston side, and a fresh working cycle begins. A second fresh working cycle has already begun during the working cycle which has just been described so that the beginning of two successive periods takes place during one whole period. Herefrom results that, by one single cylinder of approximately normal size and by one smaller cylinder of only $\frac{1}{3}$ the size of the other, the work of two cylinders of normal size working in ordinary four stroke cycle is supplied. As further progress the absolute and rapidest admixing of the air for combustion with the fuel, even at the highest number of revolutions, may be mentioned.

Further advantages result therefrom that, in opposition to an engine with double acting cylinder of commonly used construction, the stuffing box is more easily accessible as it is situated on the upper end and has to pack only against air of less than 3 atoms. The working cylinder, or the anchors which connect the same to the engine casing, have to take up only about $\frac{1}{10}$ th of the otherwise occurring forces in the direction of the cylinder axis. The cam shaft *s* can be mounted at the side of the valve case *e* without a vertical intermediate shaft, merely with interposition of simple spur gearing so that, with the exception of the suction valve *m* mounted at the side of the stuffing box, all other valves can be directly controlled.

Owing to the great length of the connecting rods *l* belonging to the working piston *g* only very feeble lateral forces occur in the connecting rod bearings so that no separate crosshead guide is necessary. These rods are further submitted only to tensile stress, as the work of the pre-compression is effected already at low number of revolutions by the pressure of the masses of the working piston. These rods can therefore be thin and light.

As the working piston *g* is guided by the piston rod *h*, it needs not be longer than necessary to accommodate the piston rings.

The cylinder is therefore comparatively short, wherefrom results low height of the engine and saving in weight.

In order to reduce the length of the three times cranked crank shaft, the outer crank arms are constructed as roller bearings *p*.

The improved engine is adapted to serve as high speed vehicle motor owing to its operation, and several such engines may be united.

I claim:

1. An internal combustion engine, comprising in combination a lower compressor cylinder, a working cylinder above said compressor cylinder, means for admitting air for combustion into said working cylinder into the upper end of the same, a low pressure conduit

on the other side of the upper end of said working cylinder adapted to conduct into said compressor cylinder the air for combustion sucked into said working cylinder, a valve box between said working cylinder and said compressor cylinder, and a fuel nozzle in said valve box along which said highly compressed and highly heated air for combustion is conducted into said working cylinder.

2. An internal combustion engine, comprising in combination a lower short compressor cylinder, an upper longer working cylinder of the same diameter as said compressor cylinder, a piston in said compressor cylinder, a piston in said working cylinder adapted to carry out a several times greater stroke than said compressor piston said pistons working in opposite directions, a crank shaft below said compressor cylinder, one

crank for said compressor piston, two outer cranks for said working cylinder these cranks displaced 180° plus the injection angle with regard to the crank of said working piston, a stuffing box on the cover plate of said working cylinder, a piston in said working cylinder, a piston rod of said working piston extending through said cover plate, a horizontal transverse piece on the top end of said piston rod symmetrically extending at both ends over the sides of said working cylinder, two connecting rods connecting the ends of said transverse piece to the corresponding crank for said working piston, a valve for sucking air for combustion into said working cylinder arranged at one side of said stuffing box, a valve box inserted between said compressor cylinder and said working cylinder, a low pressure conduit on the other side of said stuffing box ending in said valve box adapted to conduct the pre-compressed air for combustion from said working cylinder into said compressor cylinder, and a fuel nozzle in said valve box along which the air for combustion highly compressed and highly heated in said compressor cylinder passes to flow into said working cylinder.

In testimony whereof I affix my signature.

WOLFGANG KNOCHENHAUER.
